UNITED STATES PATENT OFFICE.

SAMUEL F. MYERS, OF NEW YORK, N. Y.

DESIGN FOR A SPOON.

SPECIFICATION forming part of Design No. 21,462, dated April 12, 1892.

Application filed March 19, 1892. Serial No. 425,626. Term of patent 3½ years.

To all whom it may concern:

Be it known that I, SAMUEL F. MYERS, a citizen of the United States, residing in the city and State of New York, have invented a new Design for a Spoon, of which the following is a specification.

The leading features of this design are the design of the arabesque pattern on the handle and of the turreted building in the bowl of the spoon.

This design for a spoon is represented in the accompanying drawing. The outline of the handle is tapering and rounded at the wider end, and there are scroll ornaments a

in relief and arabesque ornaments at b, also 15 in relief, and a vermiculated border c around the space for a name, and in the bowl of the spoon is a design representing a building with turrets.

What I claim is—

The design for a spoon, substantially as shown and described.

Signed by me this 17th day of March, 1892.

SAMUEL F. MYERS.
